UNITED STATES PATENT OFFICE.

JOHN BOYD, OF LA GRANGE, INDIANA.

CAR-COUPING.

SPECIFICATION forming part of Letters Patent No. 269,176, dated December 19, 1882.

Application filed May 12, 1882. (No model.)

To all whom it may concern:

Be it known that I, JOHN BOYD, of La Grange, in the county of La Grange and State of Indiana, have invented a certain new and Improved Automatic Car-Coupling; and I do hereby declare the following to be a full, clear, and exact description of the same, reference being had to the accompanying drawings, forming part of this specification, in which—

10 Figures 1 and 2 represent longitudinal sectional views of the coupling in different positions. Fig. 3 is a front elevation of the coupling; Fig. 4, a top view, and Fig. 5 a bottom view, of the same.

15 Similar letters of reference in the several figures denote the same parts.

My invention has for its object to provide a car-coupling which can be set to couple automatically with an approaching car, and which 20 can be adjusted so as to couple with cars of different heights or be uncoupled without the necessity of going between the cars for either of such purposes.

To these ends the invention consists, first, 25 in improved means for holding the coupling-pin elevated until released by the approaching car; secondly, in means for holding the link in line with the draw-head, so as to insure its entrance into the draw-head of the opposite car; thirdly, in the improved manner of 30 mounting the draw-bar; fourthly, in improved means for elevating the draw-head to effect a coupling with cars of different heights; and, fifthly, in certain details of construction and 35 combinations of parts, all of which I will first describe, and then point out specifically in the claims.

In the accompanying drawings, the draw-head of the coupling is shown constructed in 40 two parts, A and B. The part A consists of an enlarged central portion, a, a forward bifurcated extension, a', and a rear extension, a'', while the part B consists of a collar, b, a tubular portion, b', and a draw-head proper, b''. The 45 part B is adapted to slide back and forth upon the part A, and a pin or bolt, c, passing through the collar b and extending through the slot of the bifurcated extension, limits the motion of said part B upon part A and prevents said part 50 B from turning. The portion b' is adapted to

play back and forth in and be supported by a U-shaped guiding and supporting yoke, D, while the rear extension or bar, a'', of the part A is adapted to work with slight play in and be supported by an oscillating guide-block, 55 E, whose journals g are mounted in suitable bearings, h, secured to the under side of the car, as shown. Mounted upon the extension or bar a'', between a flange or collar, f, and the block E, is a spiral spring, I. Also mounted on the 60 bar a'', in rear of the block E, and between it and a screw-nut, J, is another spiral spring, K. These springs operate to prevent serious concussion and breaking of the parts when the cars are started or stopped. Pivoted between 65 flanges on the upper part of the enlarged portion a of part A is a bell-crank lever, L, the forward arm of which is provided with a plate or block, l, and the rear or upper arm of which is connected by a short chain, m, to a lever, M, 70 operated by a rod, N, or other contrivance, arranged at the side of the car, or on the platform, or on the top of the car, as desired. Another chain, o, is secured to the forward arm of the bell-crank, and extends thence under a small anti-friction pulley, p, thence around a second pulley, q, and thence forward to the pin or bolt c on the movable part B of the draw-head, to which it is connected. The forward end of the part a' is open and adapted 75 to receive and hold in a horizontal position the coupling-link Q, as will be hereinafter described. Mounted upon the draw-head proper, b'', is a metal plate, R, of rectangular shape, and adapted to play back and forth in a slot, 80 r, in said draw-head proper, as shown in Figs. 1 and 2. A perforation, s, is made vertically through both parts of the plate R, and a corresponding perforation, t, is made in the upper portion of the draw-head proper, and another 85 perforation, t', in the lower part of the same. When the plate R is drawn forward the coupling-pin U, inserted therein, will rest upon or near the edge of the perforation t; but when the plate R is struck or moved back by the 90 draw-head of the approaching car the pin is moved back and drops down through both perforations in the draw-head proper, and also through the link entered therein, thus effecting the coupling.

When it is desired to couple a car having the link in its draw-head with a car set for coupling, but having no link, it is necessary to first bring the link substantially parallel to the length of the draw-bar in order that it may be properly directed into the mouth of the draw-head proper of the car to which connection is to be made. To accomplish this it is only necessary for the operator from his position at the side, on the platform, or on the top of the car to move forward the rod *N*, which swings the lever *M*, and causes said lever to draw upon the chain *m* and rock the bell-crank lever *L* backward. The rocking of the bell-crank lever causes it to draw upon the chain *o* and slide backward bodily the part *B* of the coupling, and causes the coupling-pin to draw the link into the open end or throat of the part *a'*, as shown in Fig. 1, thus drawing the link into horizontal position.

As a means for raising and adjusting the draw-head vertically, so as to enable the link to be entered into the draw-head of a car of any height, I provide a bell-crank lever, *V*, pivoted in a slot of the U-shaped guiding and supporting yoke at *r*, and adapted to be rocked by means of a rod, *W*, extending to the side of the car and operated at the side of the car, or by suitable contrivances from the platform or top of the car. This arrangement enables the draw-bar to be raised and lowered and kept under perfect control in entering the link in the draw-head of the approaching car. As soon as the coupling is effected and the cars start up, the link is drawn out of the open end or mouth of the part *a'*, and, catching onto the pin, draws, by means of the pin, the part *B* of the coupling forward. When the part *B* reaches the limit of its forward movement the plate or block *l* on the forward arm of the bell-crank lever *L* drops down between the collar *b* of the part *B* and the enlargement *a* of the part *A*, and locks the parts *A* and *B* from further longitudinal movement upon each other in either direction. A rod or bar, *x*, projects rearward from the part *A* through a perforation in the oscillating guide-block *E*, and prevents the draw-bar from turning on its longitudinal axis. The tubular portions *a* and *b* of the parts *A* and *B* respectively being slotted longitudinally, as above described, any sand or dirt entering through the mouth of the draw-head

or elsewhere will at once work out and be prevented from lodgment and not interfere with the operation of the parts.

The various parts of the coupling may be made of wrought-iron and boiler-iron or cast-iron, as may in practice be found most desirable.

Having thus described my invention, I claim as new—

1. The combination, with the draw-bar supported at its rear ends by the oscillating block *E*, and guided and supported at its forward end by the guide-yoke *D*, of the bell-crank lever *V* and the rod *W*, whereby the outer end of the draw-bar carrying the link is enabled to be raised or lowered, so as to cause the link to enter the draw-heads of cars of different heights, substantially as described.

2. The combination, with the part *A* of the draw-head, of the part *B*, sliding thereon, and the bell-crank lever and chain *o* for effecting the backward movement of the part *B*, substantially as described.

3. The combination of the part *A* and the part *B*, sliding thereon, with the bell-crank lever having the block or plate *l*, adapted to lock the parts *A* and *B* from longitudinal movement in either direction, substantially as described.

4. The combination, with the stationary part *A*, having the open end or throat for receiving the link, of the sliding part *B* and the coupling-pin, whereby upon the rearward movement of the part *B* the link is drawn within the throat of part *A* and maintained in horizontal position, substantially as described.

5. The combination, with the rearward extension *a'* of the part *A*, of the oscillating guide-block *E* and the springs *I* and *K* on opposite sides of said block, substantially as described.

6. The combination, with the rearward extension *a'* of the part *A*, of the guide-block *E* and the bar *x*, working through a perforation in the block *E*, and operating to prevent the turning of the draw-bar on its longitudinal axis, substantially as described.

JOHN BOYD.
